US00D784424S

(12) **United States Design Patent** (10) **Patent No.:** **US D784,424 S**
Renski et al. (45) **Date of Patent:** **** Apr. 18, 2017**

(54) **ADAPTER FOR A GROUND ENGAGING MACHINE IMPLEMENT**

(71) Applicant: **Caterpillar Inc.**, Peoria, IL (US)

(72) Inventors: **William J. Renski**, Peoria, IL (US);
James Robert Lahood, Peoria, IL (US)

(73) Assignee: **Caterpillar Inc.**, Peoria, IL (US)

(**) Term: **15 Years**

(21) Appl. No.: **29/548,613**

(22) Filed: **Dec. 15, 2015**

Related U.S. Application Data

(62) Division of application No. 29/517,592, filed on Feb. 13, 2015, now Pat. No. Des. 749,145, which is a division of application No. 29/488,787, filed on Apr. 23, 2014, now Pat. No. Des. 727,369, which is a division of application No. 29/403,594, filed on Oct. 7, 2011, now Pat. No. Des. 707,264.

CLAIM

The ornamental design for an adapter for a ground engaging machine implement, as shown and described.

DESCRIPTION

FIG. 1 is a perspective view of an adapter for a ground engaging machine implement showing our new design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is a bottom rear left perspective view thereof; and, FIG. 9 is a top rear left perspective view thereof.

The broken lines illustrate structure or features that form no part of the claimed design.

1 Claim, 6 Drawing Sheets
